UNITED STATES PATENT OFFICE.

HUBERT BROSSEL, OF INDIANAPOLIS, INDIANA.

BUTTON-FASTENER.

SPECIFICATION forming part of Letters Patent No. 299,110, dated May 27, 1884.

Application filed November 12, 1883. (No model.)

To all whom it may concern:

Be it known that I, HUBERT BROSSEL, a citizen of the United States, residing at Indianapolis, in the county of Marion and State of Indiana, have invented certain new and useful 5 Improvements in Button-Fasteners, of which the following is a specification.

My invention relates to improvements in the method of fastening buttons to fabrics or 10 leather; and the objects of my improvements are to provide a simple and cheap fastening, one which necessitates the cutting or punching of but one hole through the fabric or leather which the button is to be secured to, 15 and one which will not discomfort the wearer of the garment or shoe, and which is easily and quickly applied. I attain these objects by the device illustrated in the accompanying drawings, in which—

20 Figure 1 is a perspective view of the button and my improved fastening; Fig. 2, a vertical section through the button and the fastening when secured to a garment or shoe, and Fig. 3 an under side view of the washer-plate forming 25 part of the fastener.

Similar letters refer to similar parts throughout the several views.

A is the button; a, the shank and eye of the same. B and C form my improved fastening. 30 B is formed by passing one-half of a piece of wire through the eye a of the button and twisting the two ends, so that the wire forms a loop for the eye a, and a stem to pass through the thickness of the fabric or leather D. The twisted 35 ends of the wire are flattened out by a stroke of a hammer, forming the head b. C is a washer-plate stamped out of metal, wood, or other like material, with a rounded surface and a slot, c, to the center.

40 To secure the button to a shoe or garment,

a hole is punched through the leather or fabric, the fastener B is inserted from the outside into the hole, the washer-plate C is slipped over the stem of the fastener, with the rounded surface toward the inside of the shoe or garment, and the two sides of the slot c are then pressed together, thus preventing the fastener B from slipping out again, and securing it rigidly in place with the washer C. The flattened head b of the stem B prevents its being pulled 45 out from the washer C. 50

The twisting of the fastener B and the stamping of the washer C being done by machinery, and the method of applying the same being so simple, make my fastening a cheap and useful article. 55

By my method of fastening a button to a garment or shoe but one hole is to be cut through the material, and the loop on the fastener will allow the button to be bent or twisted 60 without affecting the washer-plate at the inside of the shoe or garment.

What I claim, and desire to secure by Letters Patent, is—

The combination, with a button provided 65 with a shank and eye, of the fastener B, formed out of wire twisted into a loop to receive the eye a of the button A, and having a flattened head, b, and the rounded washer-plate C, provided with a slot, c, to receive the fastener B, 70 substantially as described, and for the purpose specified.

In testimony whereof I have signed my name to this specification in the presence of two subscribing witnesses.

HUBERT BROSSEL.
